UNITED STATES PATENT OFFICE.

WALTER J. CARRIER, OF LANSING, MICHIGAN.

WATER AND FIRE SHIELD FOR CHIMNEYS.

1,158,117.

Specification of Letters Patent.

Patented Oct. 26, 1915.

Application filed June 9, 1915. Serial No. 33,137.

To all whom it may concern:

Be it known that I, WALTER J. CARRIER, a citizen of the United States, residing at Lansing, in the county of Ingham and State 5 of Michigan, have invented certain new and useful Improvements in Water and Fire Shields for Chimneys; and I do hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in water and fire shields for chimneys and comprises a simple and efficient device of this nature, having various 20 details of construction, combinations and arrangements of parts which will be herein-after fully described, shown in the accompanying drawings and then specifically defined in the appended claims.

25 I illustrate my invention in the accompanying drawings, in which:

Figure 1 is a perspective view of a shield with the parts adjusted in place upon a roof. Fig. 2 is a sectional view taken on 30 line 2—2 of Fig. 1. Fig. 3 is a sectional view taken on line 3—3 of Fig. 1, and Fig. 4 is a perspective view of the parts disassembled.

Reference now being had to the details of the drawings by letter, A, A designate two 35 sides of the fire shields of the apparatus which have flanges A¹ projecting from the upper edges thereof and at right angles thereto and which are adapted to engage the roof underneath the shingles in the manner shown clearly in Fig. 2 of the drawings, and at the ends of said sides are flanges C 40 projecting parallel to each other and adapted to engage underneath the end plates B which have flanges B^x at their ends and a downwardly inclined flange B¹, as shown clearly in Figs. 3 and 4 of the drawings.

A frame E, having a central opening for the reception of a chimney A^x, has a circumferential flange E^x. When the parts A and B are 50 assembled together, the flanges C extend underneath the downwardly inclined flanges B¹ and both the ends and the sides A and B respectively rest upon the upper surface of the frame E with their lower ends surrounded by the flange E^x. It will be understood 55 that the licks of the chimney are adapted

to rest upon the frame E in the manner shown in Figs. 2 and 3 of the drawings.

The water shield comprises the end plates F with parallel flanges F² upon the opposite sides and an inclined portion F¹ with ends projecting beyond the opposite ends of the flanges F² and each projection is provided with a transverse beading F³, as shown clearly in the drawings, and which extensions are adapted to pass underneath the shingles of the roof. The sides of the water shield are designated by letter H, there being two of similar construction, each having a vertically disposed flange H¹ at its outer 70 end and which flanges H¹ have their ends H^x bent to form a downwardly extending hook which, when the parts are assembled, engage over the upper edges of the ends F.

Upon reference to Fig. 4 of the drawings, 75 it will be noted that the sections of the water shield H have laterally projecting inclined flanges H², which terminate at their upper ends in flanges H⁴ adapted to overlap each other and at the inner marginal edge 80 of the inclined portion of each section H is an upwardly turned flange L forming a gutter intermediate the same and a beading H³, which latter is adapted to fit over the beading F³, as shown in Fig. 2 of the drawings. 85

An adjustable cap J is adapted to fit over the upper ends of the sections of the water shield and one end of the cap has its flange at one end, designated by letter J¹, adjustable so that it may be properly fitted to the water shield sections and has upwardly extending flanges J² which are adapted to engage between the brick of the chimney, and which serves as a means for securely anchoring 95 the fire shield to the latter.

By the provision of a water and fire shield made in accordance with my invention, it will be noted that the parts will be securely held in place by the chimney and by the 100 interlocking beadings, the parts securely anchored together and, by the provision of the gutters formed on either side of the chimney, water will be prevented from leaking through the joints intermediate the 105 parts.

What I claim to be new is:—

1. A water and fire shield for chimneys, comprising a frame with an opening for the reception of a chimney and having an upwardly extending flange about its marginal edge, end fire shield sections having later-

ally extending and parallel flanges at the ends thereof and adapted to rest upon said frame, inclined flanges at the upper ends thereof, side fire shields, having laterally 5 extending flanges at the ends engaging underneath said downwardly inclined flanges and resting upon the frame, each side shield provided with outwardly inclined flanges, water shields comprising flanged end sections 10 engaging said inclined flanges of the fire shield and having laterally extending wings which are transversely beaded, sectional side water shields with flanges provided with beadings adapted to fit over said 15 beadings upon the extension of the end sections, and a cap fitted over the water shields.

2. A water and fire shield for chimneys, comprising a frame with an opening for the reception of a chimney and having an upwardly extending flange about its marginal edge, end fire shield sections having laterally extending and parallel flanges at the ends thereof and adapted to rest upon said frame, inclined flanges at the upper ends 20 thereof, said fire shields having laterally extending flanges at the ends engaging underneath said downwardly inclined flanges and resting upon the frame, each side shield provided with outwardly inclined flanges, 25 water shields comprising flanged end sections engaging said inclined flanges of the fire shield and having laterally extending wings which are transversely beaded, sectional side water shields with flanges provided with beadings adapted to fit over said 30 beadings upon the extension of the end sections, said sectional shields having vertical flanges with their upper ends bent to form hooks to engage over the upright portions 35 of the end water shields, and a cap fitted over the upper ends of the water shields.

3. A water and fire shield for chimneys, comprising a frame with an opening for the reception of a chimney and having an upwardly extending flange about its marginal edge, end fire shield sections having laterally extending and parallel flanges at the ends thereof and adapted to rest upon said frame, inclined flanges at the upper ends 40 thereof, said fire shields having laterally extending flanges at the ends engaging un-

derneath said downwardly inclined flanges and resting upon the frame, each side shield provided with outwardly inclined flanges, water shields comprising flanged end sections 55 engaging said inclined flanges of the fire shield and having laterally extending wings which are transversely beaded, sectional side water shields with flanges provided with beadings adapted to fit over 60 said beadings upon the extension of the end sections, said sectional shields having vertical flanges with their upper ends bent to form hooks to engage over the upright portions 65 of the end water shields, and a sectional cap fitted over the water shield and provided with an upwardly extended flange adapted to be engaged by the masonry work 70 of the chimney.

4. A water and fire shield for chimneys, comprising a frame with an opening for the reception of a chimney and having an upwardly extending flange about its marginal edge, end fire shield sections having laterally extending and parallel flanges at the 75 ends thereof and adapted to rest upon said frame, inclined flanges at the upper ends thereof, said fire shields having laterally extending flanges at the ends engaging underneath said downwardly inclined flanges 80 and resting upon the frame, each side shield provided with outwardly inclined flanges, water shields comprising flanged end sections engaging said inclined flanges of the fire shield and having laterally extending 85 wings which are transversely beaded, sectional side water shields, each having a laterally extending side flange with a beading formed therein and an inwardly extending vertically disposed flange terminating in a 90 hook at its upper end, an upwardly turned flange along the inner edge of the inclined flange thereof, the upper ends of the inclined flanges adapted to overlap, and a cap fitted over the upper ends of the water 95 shield.

In testimony whereof I hereunto affix my signature in presence of two witnesses.

WALTER J. CARRIER.
